UNITED STATES PATENT OFFICE

2,170,934

CONVEYER

Albert F. White, Toronto, Ontario, Canada

Application June 2, 1939, Serial No. 277,059

5 Claims. (Cl. 198—168)

This invention relates to a conveyer, and an object of the invention is to provide a conveyer having pivotally attached trailing flights for conveying material, with simple but very efficient means for swinging the flights to a material discharging position adjacent a discharge opening.

Another object of the invention is to provide an improved chain and flight hanger construction for an endless chain conveyer.

10 Other objects of the invention will appear hereinafter, the novel features and combinations being set forth in the appended claims.

In the accompanying drawing,

15 Fig. 1 is a side elevational view of a conveyer comprising my invention, with parts broken away to show in detail the structure of the conveyer chain and flights;

20 Fig. 2 is an enlarged side elevational sectional view of a portion of the conveyer adjacent the top thereof;

Fig. 3 is a sectional view taken on the line 3—3 of Fig. 1, looking in the direction of the arrows;

25 Fig. 4 is a sectional view taken on the line 4—4 of Fig. 1, looking in the direction of the arrows; and

Fig. 5 is an enlarged sectional view showing the structure of the conveyer chain and flight attaching mechanism.

The conveyer of my invention comprises a 30 frame or casing 10 formed of top section 11, bottom section 12 and intermediate sections 13 and 14. It will be understood that the number of intermediate sections 13 and 14 may be varied as desired and may have any desired configuration.

35 In the drawing the frame or casing 10 is generally L-shaped but it will be understood that any other desired shape may be provided.

The bottom section 12 is provided with a material receiving hopper 15 below which is a double 40 partition 16 which forms the top portion of a working leg 17 and the bottom portion of a return leg 18 of the frame or casing 10. The intermediate section 13 is formed of two spaced-apart substantially totally enclosing housings, as clearly 45 illustrated in Fig. 1 of the drawing, and is preferably formed substantially rectangular in cross-section though the shape may be round or any other desired shape. The intermediate section 13 converges at its top and connects to intermediate 50 section 14 in which the working leg 17 and return leg 18 are formed with a common intermediate wall 19, best seen in Fig. 3 of the drawing. The wall 19 continues into the top section 11, as best 55 illustrated in Fig. 2 of the drawing, and said top

section 11 includes an enlarged housing provided with a discharge opening or nozzle 20.

Within the frame or casing 10 is an endless chain conveyer 21 the working run of which extends through the working leg 17 and the return 5 run of which extends through the return leg 18. The endless chain conveyer 21 is formed of a draft mechanism in the form of a plurality of pivotally attached chain links 22, the structure of which is best seen by reference to Figs. 4 and 5 of the 10 drawing. Each of said chain links 22 is provided with an integral arm 23 at one end of which is pivotally attached a flight 24 by means of a hang rod 25, the hang rod 25 being rigidly attached to the flight 24 and pivoted to arm 23 by pin 26. The 15 hang rod 25 and arm 23 carry co-operating abutments 27 and 28, respectively, (see Fig. 5) which limit the pivotal movement of the flight 24 and hang rod 25 away from the link 22 so that each flight 24 gradually approaches the housing of the 20 return leg 18 in proper position, as clearly illustrated in Fig. 2 of the drawing.

As best illustrated in Figs. 3 and 4 of the drawing, each of the flights 24 approximately fills the cross-section of the working leg 17 as well as the 25 return leg 18. However, to provide free pivotal movement of the flights 24 with respect to the links 22 of chain 21, each of said flights is centrally notched at 29 which allows a liberal amount of free movement between said flights 24 and links 30 22. This is particularly important during the travel of the chain conveyer 21 around curves or in case the legs 17 or 18 of the housing are not entirely straight. Furthermore, it provides for a free discharge of the material by swinging the flights 35 to a discharge position even though the working leg 17 is substantially vertical at the point of discharge.

As above indicated, the flight 24 approximately fills the cross-section of the working leg 17. By 40 this expression it is meant that material does not form as a continuous column or move as a unitary mass in the working leg 17, but the material being conveyed is separated by the successive flights 24. It is to be understood, however, that 45 the flights 24 may be of a frame-like structure and permit the material which is conveyed through the working leg 17 to be transported as a mass or substantially fill the working leg 17 without the above mentioned separation or segregation.

The endless chain conveyer 21 is preferably mounted on a top sprocket 30 which is double in character in that the teeth extend on each side of each link 22. The sprocket 30 is keyed to shaft

31 mounted in suitable bearings in the top section 11 and driven from a motor 32 mounted on a platform 33, through appropriate drive mechanism 34. The bottom section 12 is also preferably provided with a sprocket 35, although a sprocket at this position is not essential if the housing is formed into a loop of large area. The sprocket 35 when provided is preferably adjustable to adjust the tension on the chain conveyer 10 21.

To provide for the efficient discharge of material elevated by the flights 24 as they reach the position adjacent the discharge opening 20, I provide mechanism for tilting said flights 24 at said discharge position preferably in the form of a pair of cams 36 which are attached to the side walls of the top section 11 and to the wall 19 of said top section 11, as clearly illustrated in Figs. 2 and 4 of the drawing. As is manifest by reference to said Fig. 2, each flight 24 will be swung outwardly to insure a thorough discharge of any material being conveyed by way of the discharge opening or nozzle 20.

In the operation of the device comprising my invention, the material to be fed, which will generally be in the form of granular material such as grain, coal, and numerous other granular or bulk materials, will be fed to the hopper 15 and fall on the top portion or partition 16. The flights 24 30 will scrape the material to the left, as viewed in Fig. 1 of the drawing, until it falls over the end thereof and enters the bottom opening or entrance to the working leg 17 from where it is conveyed through said working leg 17 by the flights 24 in co-operation with the substantially totally enclosing working leg 17 of the frame or casing 10.

As previously indicated, the material between the successive flights 24 will be segregated or separated, but if a frame-like flight is substituted for the flights 24 the material may move substantially in mass in the column of working leg 17. As the material reaches the discharge opening or nozzle 20 it will tend to flow therefrom, due to its granular condition, and to assure a complete discharge of the material from the flights 24 said flights are tipped by being swung outwardly, as clearly illustrated in Fig. 2 of the drawing.

As the flights 24 move over the sprocket 30 their swinging movement is restricted by the co-operating stops 27 and 28 so that said flights move gradually into contact with the outer wall of the casing of return leg 18. It is of course evident that during the conveying of material through the working leg 17 the flights 24 are dragged along in a trailing fashion by the chain 21 and are free to follow the contour of said leg 17 by virtue of the fact that they are free to move with respect to the links 22 of chain conveyer 21. This insures against binding of the flights and reduces wear on the casing and on the flights and as well keeps the amount of power consumed in the operation of the conveyer, at a minimum.

It is furthermore to be noted that the pull on the conveyer chain 21, particularly around the curved intermediate section 13, is not in any manner assumed by the flights 24 but is assumed by a direct contact between the inner face of the chain 21 and the inner wall of the casing of said intermediate section 13. This further prevents any binding of the conveyer while moving through the frame or casing 10.

Obviously those skilled in the art may make various changes in the details and arrangement of parts without departing from the spirit and scope of the invention as defined by the claims hereto appended, and I therefore wish not to be restricted to the precise construction herein disclosed. 5

Having thus described and shown an embodiment of my invention, what I desire to secure by Letters Patent of the United States is:

1. In a conveyer, the combination with a casing having an upwardly extending substantially entirely enclosing leg and a discharge opening, endless draft mechanism in said casing for conveying material along said casing leg to said discharge opening, trailing pivoted flights carried by said endless draft mechanism and cooperating with said leg to convey material to said discharge opening said flights having openings through which said draft mechanism freely passes while providing for lateral movement of said flights relative thereto, and cam means for swinging said flights to material discharging position adjacent said discharge opening. 10 15 20

2. In a conveyer, the combination with a casing having enclosing side walls forming an upwardly extending substantially entirely enclosing conveying leg, of an endless conveyer chain running through said leg, a discharge opening on said leg, a plurality of flights having hang rods pivotally attached to said endless conveyer chain ahead of said flights and having openings through which said chain freely passes, and mechanism comprising duplicate cams on opposite sides of said chain for swinging said flights away from said endless conveyer into discharging position adjacent said discharge opening. 25 30 35

3. In a conveyer, the combination with a casing having enclosing side walls forming an upwardly extending substantially entirely enclosing conveying leg, of an endless conveyer draft means running through said leg, a discharge opening on said leg, a plurality of flights having hang rods pivotally attached to said endless conveyer draft means ahead of said flights and having notches through which said draft means freely passes, and a cam for swinging said flights away from said endless conveyer draft means into discharging position adjacent said discharge opening. 40 45 50

4. In a conveyer, the combination with a substantially entirely enclosing casing, of an endless conveyer chain running through said casing, flights having hang rods pivotally attached to said endless conveyer mechanism ahead of said flights and having notches freely receiving said chain, and cooperating abutments on said hang rods and conveyer chain for restricting the swinging movement of said hang rods away from said conveyer chain. 55 60

5. In a conveyer, the combination with a substantially entirely enclosing casing, of endless draft mechanism running through said casing, trailing flights having hang rods pivotally attached to said endless draft mechanism and having openings through which said draft means freely pass while providing for lateral movement of said flights relative thereto, and cooperating abutments on said hang rods and draft mechanism for restricting the swinging movement of said hang rods relative to said draft mechanism. 65 70

ALBERT F. WHITE.
